LEONARD S. COPELIN, OF LOS ANGELES, CALIFORNIA

EXPANDING ROTARY UNDERREAMER

Application filed March 21, 1928. Serial No. 263,331.

My invention relates to the art of drilling oil wells and the like, being more particularly an underreamer of the rotary type. In the drilling of oil wells, it is customary to clean the sides of the hole after the drilling tool has advanced, so that the string of pipe to be set may be readily lowered into proper position without friction, and for this purpose, it is customary to use an underreamer which cuts the hole to a sufficiently large diameter above the bit to permit the string of pipe to be set.

Underreamers, whether of the blade type, or the type in which rotary cutters are employed, usually are provided with positive means for expanding the underreaming elements, which positive means is operated by means of movable parts in the body of the underreamer, which, in turn, are operated to move longitudinally with respect to the body of the underreamer.

It is the principal object of my invention to produce an underreamer of the rotary cutter type, of simple form and construction, in which no sliding members are used for expanding the cutters and in which the action of the cutters is entirely automatic and operated by engagement with the sides of the hole.

The object just referred to is accomplished by mounting a plurality of rotatable cutting units in the body of the underreamer, such rotary cutting elements being slidable longitudinally within fixed limits, and so arranged that engagement by the rotary cutting elements of the sides of the hole move such cutting elements upwardly and outwardly into expanded position, so as to enlarge the hole to a sufficient diameter to receive the casing, the cutting units moving into an inoperative position upon upward movement of the drill string.

Other objects and advantages will appear hereinafter from the following specification and the accompanying drawings.

Referring to the drawings, which are for illustrative purposes only,

Fig. 1 is a vertical sectional view through a portion of an underreamer body, showing a

form of my invention, the cutting units being shown in expanded position.

Fig. 2 is a view similar to Fig. 1, showing the cutting elements in retracted or inoperative position.

Fig. 3 is a sectional plan view on line 3—3 of Fig. 1.

Fig. 4 is a sectional plan view on line 4—4 of Fig. 1.

Fig. 5 is a sectional plan view on line 5—5 of Fig. 2.

Fig. 6 is an inverted sectional plan view on line 6—6 of Fig. 1.

Fig. 7 is a perspective view of one of the rotary cutter units.

Fig. 8 is a perspective view of a bearing block of one of the cutter units.

Fig. 9 is a perspective view of a filler block.

Fig. 10 is a perspective view of a retaining ring used for holding the bearing blocks in proper position.

Fig. 11 is an assembled view on a smaller scale of the entire underreamer and connections, as the same appear passing through the casing in the well.

More specifically describing the embodiment of my invention as shown in the accompanying drawings, 11 designates a reamer body, circular in cross section, being internally threaded at its upper end to receive a sub 12 for attachment to drill collar 13, the lower end of the reamer body terminating in a reduced threaded portion 14, to which is attached a sub 15, for attachment of any suitable form of bit, the upper end of which is indicated at 16, as shown in Fig. 11.

A plurality of reamer units are employed, in the form shown there being three such units, generally indicated at 20, each being mounted in a recess 21, formed in the side of the reamer body. Each cutting or reaming unit 20 consists of a crank shaft 22, having offset ends 23 and 24, the end 23 being fixed to an extension 25 on the main portion of the shaft by means of a pin 26 which may be secured therein by welding or other suitable manner. The upper end 23 of the crank shaft is rotatably received in a bore 27 in the upper face of the recess 21, a thrust bearing 28 being provided in the form of a ball

bearing, as clearly shown in Figs. 1 and 2. The lower end 24 of the crank shaft is rotatably received in a bore 30, extending into the upper end of a bearing block 31, mounted 5 in a guide way or slot 32, extending downwardly from the recess 21.

This block 31 is shouldered, as indicated at 33, to form a seat for offset lower end of the crank portion of the crank shaft 22, bevel 10 faces 34 and 35 being formed at the rear of said shoulder 33 to facilitate the expulsion of cuttings from the shoulder and behind the crank when the cutting or reaming elements move into retracted position.

15 Mounted on each crank shaft 22 is a reamer element consisting of a cutter or reamer in the form of a roll 36, having a series of longitudinally extending serrations or teeth 37, tapering at their lower ends, as indicated at 38. The upper end of each reamer 36 is beveled as indicated at 39 to engage against a beveled guide 40 in the upper end of the recess 21.

20 Each cutter unit 20 is assembled in the following manner: The reamer 36 is placed on the crank portion of the recess and a washer 41 placed thereon, after which the end 23 is secured to the crank portion of the shaft, as above described. The upper end 23 is then 25 inserted in the bore 27, the lower end 24 being placed in the bearing block and such block placed in the slot 32, being retained in place by means of a ring 43 on a reduced portion 44 of the reamer body, such ring being held in place by means of the sub- 30 15.

The slot 32 extends below the lower end of the block 31 to afford sufficient movement of the block to permit the end 23 of the crank shaft to be inserted as above described, a filler block 43' being placed in the slot below the bearing block 31.

40 Means are provided for discharging circulating fluid into the recesses 21, which consist of a series of ducts or passages 45, shown in Fig. 6, and such ducts connect with a chamber 46 as indicated in Fig. 11. A central fluid passage 47 extends longitudinally throughout the underreamer to supply fluid to the bit.

45 50 The operation of the underreamer is as follows: In the position shown in Fig. 11, the underreamer may be considered as passing downwardly through the casing 50, in which position it will be noted that the cutters or reamers 36 extend laterally slightly beyond the walls of the underreamer body. While in this position, the reamers are retracted and the crank portion of the crank shaft rests upon the shoulder 33 on the bearing block, 55 this retracted position of the reamers being also illustrated in Figs. 2 and 5.

60 As the tool in its downward movement reaches a point where the reamers 36 engage the sides of the hole, indicated at 51, the reamers, being shorter than the crank por-

tion of the crank shaft 22, slide upwardly thereon, the beveled end 39 of the reamers engaging their respective guides 40 and moving the reamers outwardly.

This action of the guides is to assist the 70 reamers into moving into expanded position, but the outward movement of the reamers is primarily caused by the engagement of the reamers with the walls of the hole and the rotary movement of the underreamer body, 75 as indicated by the arrow 53 in Fig. 4. The downward movement of the underreamer and the rotative movement of the underreamer cause the crank shafts with the reamers thereon to swing outwardly in the direction of the arrow 54 in Fig. 5, which outward movement is limited by the engagement of the crank portion of the crank shaft, with an abutment 55 on the bearing block 31. When the reamers are in the expanded position shown in Figs. 1 and 4, the formation is cut away to a diameter permitting the lowering of the casing as may be desired.

80 The reamers are retracted by an upward movement and a reverse rotative movement of the underreamer body from that just described, the crank shafts and reamers thereon being free to return to their original position.

85 While I have shown a preferred embodiment of my invention, it is to be understood that modifications of the construction shown may be made by those skilled in the art without departing from the spirit of my invention.

90 I claim as my invention:

95 1. An underreamer comprising a body, a plurality of crank shafts having offset ends mounted on said body, a rotatable reamer on each crank shaft, and means for limiting the rotative movement of said crank shafts.

100 2. An underreamer comprising a body, a plurality of reamer units mounted in said body, each reamer unit consisting of a crank shaft, a rotatable reamer on said shaft, a bearing block receiving the lower end of said crank shaft, and means for retaining the bearing block on said reamer body.

105 3. An underreamer comprising a body, a plurality of reamer units mounted in said body, each reamer unit consisting of a crank shaft, a rotatable reamer on said shaft, a bearing block receiving the lower end of said crank shaft, a shoulder on said bearing block arranged to support said crank shaft, means 110 on said block for limiting the rotative movement of said crank shaft, and means for retaining said block on the reamer body.

115 4. An underreamer comprising a body having a plurality of reamer recesses there- 120 in, a rotatable reamer swingably mounted in each recess, and stationary guide means engageable with the upper end of each rotatable reamer to swing said reamer into operative position.

5. An underreamer comprising a body, a plurality of crank members mounted in said body, and a reamer on each crank member slidably and rotatably mounted thereon.
- 5 6. An underreamer comprising a body, a plurality of crank members mounted in said body, a reamer on each crank member slidably and rotatably mounted thereon, and means for limiting the rotative movement of said crank members.
- 10 7. An underreamer comprising a body, a plurality of rotatable reamers swingably mounted thereon, and means operable by engagement of the reamers with the formation followed by a downward movement of said body relative to said formation to swing said reamers outwardly with respect to the longitudinal axis of said body.
- 15 8. An underreamer comprising a body, a plurality of rotatable reamers swingably and slidably mounted thereon, means operable by engagement of the reamers with the formation to swing said reamers outwardly with respect to the longitudinal axis of said body, and means engageable by said reamers during their sliding movement to direct the reamers in their outward movement.
- 20 9. An underreamer comprising: a body; a plurality of crank members rotatably mounted in said body; a reamer slidably and rotatably mounted on each crank member; and means operable upon sliding of said reamers to rotate said crank members.
- 25 10. An underreamer comprising: a body; a plurality of crank members rotatably mounted in said body; a reamer slidably and rotatably mounted on each crank member; means operable upon sliding of said reamers to rotate said crank members; and means for limiting the rotative movement of said crank members.

In testimony whereof, I have hereunto set my hand at Los Angeles, California, this 12 day of March, 1928.

LEONARD S. COPELIN.
